UNITED STATES PATENT OFFICE.

DETLEF LOUIS JOEHNCK, OF ROCKY FORD, COLORADO.

CONVEYER AND SEPARATOR.

1,297,176.

Specification of Letters Patent. Patented Mar. 11, 1919.

Application filed December 28, 1918. Serial No. 268,738.

To all whom it may concern:

Be it known that I, DETLEF L. JOEHNCK, a citizen of the United States, residing at Rocky Ford, in the county of Otero and State of Colorado, have invented certain new and useful Improvements in Conveyers and Separators; and I do hereby declare the following to be a full, clear, and exact description of the invention, such as will enable others skilled in the art to which it appertains to make and use the same.

My present invention relates to improvements for handling articles that are to be unloaded from wagons and raised to a higher elevation so that they may be dumped into a railroad car, an elevated conveyer, or into a pile, stack, bin or pit, where such material may be kept for storage. The apparatus hereinafter described may be adapted for the transfer of sugar beets, tubers, coal, stone, grain, or other similar material.

The invention, however, is especially adapted for use in connection with the transfer of beets, tubers, or other material to which there is always more or less dirt or trash attached, and from which it is desirable to remove such foreign matter as far as practicable.

The invention is especially adapted to the handling of beets, in which is is customary to haul them to cars for transportation.

It is necessary to weigh them and as such product contains more or less earth, trash, leaves and foreign matter, it is desirable to screen such beets before transporting them to the factory, thereby saving transportation of undesirable material and also removing such foreign material. Further, it is desirable to place in storage for future use and shipment a certain quantity of raw material to be used in later process of manufacture. For this purpose the apparatus is especially adapted as it may be used to pile material at considerable height and the apparatus moved from place to place with ease and thereby pile or store an unlimited amount of material at exceedingly small expense.

Furthermore, the apparatus is adapted to take care of the loose dirt or trash that falls from the beets and to carry it away, preferably in the empty carts or cars from which the beets have been fed to the apparatus. This dirt may accumulate in objectionable

piles around the apparatus, and it is frequently desirable to return this to the fields from which it came.

My invention further relates to providing an apparatus which, though more or less ponderous, can be moved from place to place and turned through the desired angle so as to build up a large pile without the necessity for spreading the beets on the pile manually.

Various other objects of the present invention will be more fully understood after reference to the accompanying drawings, in which similar parts are indicated by similar reference symbols throughout the several views, and in which:

Figure 1 shows a side elevation of the complete apparatus, one of the supports for the cart tilting apparatus being broken away for the sake of clearness in the drawings.

Fig. 2 is a plan view showing the complete apparatus with the various parts thereof, but it does not show the wagons feeding the apparatus.

Fig. 3 shows a section along the line 3—3 of Fig. 1, and looking in the direction of the arrows, the parts being shown on a larger scale, and one of the feeding wagons being shown in the dumping position and another wagon being shown in the position to receive the dirt screened from the beets.

Fig. 3^a is a detail showing one of the clutch mechanisms for operating one of the drums for tilting the corresponding wagon bottom.

Fig. 3^b shows a section along the line 3^b—3^b of Fig. 3^a, and looking in the direction of the arrows.

Fig. 4 is a sectional view of the delivery end of the apparatus, on a still larger scale, the parts being shown in section along the line 4—4 of Fig. 5, and looking in the direction of the arrows.

Fig. 5 is a plan view of the delivery end of the apparatus, parts being broken away.

Fig. 6 shows a section along the broken line 6—6 of Fig. 5, and looking in the direction of the arrows, and illustrates the means for diverting the dirt screened out to one side or the other of the apparatus.

Fig. 7 is a plan view of the parts shown in Fig. 6, with the grid screen broken away.

Fig. 8 shows a section along the line 8—8 of Fig. 2, parts being broken away, and illustrates the means for deflecting the

screened dirt from one side or the other of the apparatus.

Fig. 9 is a side view of the parts shown in Fig. 8, parts being shown as broken away.

Fig. 10 shows a side elevation, on a larger scale, of a part of the forward end of the apparatus.

Fig. 11 shows a section along the line 11—11 of Fig. 10, and looking in the direction of the arrows, the supporting wheel being shown in elevation.

Fig. 12 shows a section along the line 12—12 of Fig. 10, and looking in the direction of the arrows.

Fig. 13 shows a section along the broken line 13—13 and 13^a—13^a of Fig. 10, and looking in the direction of the arrows.

Fig. 14 shows a section along the line 14—14 of Fig. 4, and looking in the direction of the arrows.

Fig. 15 shows a section along the line 15—15 of Fig. 4; and

Fig. 16 shows a section along the line 16—16 of Fig. 4.

A represents the main frame supported on the front wheel B and rear wheels B'. These wheels are preferably mounted in swivel bearings so that the wheels may be turned like a caster for steering and guiding the main frame and the parts carried thereby.

Thus, referring to Figs. 1, 2, 10 and 11, I have shown the front wheel B carried by an axle b, whose ends are journaled in the bearings c beneath the flange ring C which engages beneath an inwardly-projecting annular flange of the supporting ring D, which is preferably I-shaped in cross section, and is secured to the main frame A.

The wheels B' are similarly mounted on the axles b' journaled beneath the rings B² carried by the laterally projecting brackets or frames B², as shown in Figs. 1 and 2.

The axes of these wheels may be shifted through an angle horizontally in any convenient way, and suitable anti-friction bearings, not shown, may be provided between the flanges of the rings C and D, or the corresponding supports for the rear wheels, but I have not deemed it necessary to complicate the specification or drawings by illustrating these details.

Mounted above the main frame A, near its forward end, are two tables E, which may be in the form of metal plates, or preferably wood faced with wear plates e, as shown in Figs. 10 and 13. Beneath these tables I provide a series of racks engaging pinions F mounted on the shaft f. This shaft is provided with a ratchet wheel F', which may be turned by the spring pawl f' carried by the hand lever F², but instead of rotating this shaft by hand it may be rotated by power if desired.

Each table E has supporting blocks e², see Fig. 10, which rest on the side beams of

the conveyer, as will be hereinafter described, and each table may be held against longitudinal movement by rods E' which pass through eye-bolts e² carried by the table and through eye-bolts h² carried by the side bars h of the conveyer frame H, see Fig. 13.

These rods have upwardly projecting ends t² which serve as supports for the directing board E², see Fig. 3, for purposes that will be hereinafter described.

G represents the main conveyer on which the beets or other articles to be separated are dumped from the wagons, cars, or other vehicles used in transporting same. This conveyer is in the form of an endless apron 80 passing over the drum G' near the front end of the main frame, as shown most clearly in Figs. 1, 2 and 10. The apron is tightened by any suitable adjusting means G², see Fig. 10, and passes beneath the idler g and above 85 the cylindrical rollers g², thence beneath the idler g', whence it travels over the double cone rollers g⁴, see Figs. 1, 4 and 14.

These rollers permit the belt to sag in the middle to form a trough, as shown in 90 Fig. 14, the belt traveling between the side bars h of the conveyer frames H and H'. The conveyer belt then passes over the upper drum G², carried by the upper end of the conveyer frame H', and then above suitable 95 guide rollers g² back to the forward drum G'. The drum G² is mounted on the shaft g² which carries the driving pulley G³, which is driven as will be hereinafter described.

The conveyer frame is composed of two members, the lower member H being secured to the main frame beneath the tables E, and the upper member H' of the conveyer frame being hinged like a derrick so that this member H' may be swung up or down through a limited angle, as may be desired.

The frame is raised or lowered by means of the cables I, see Figs. 1 and 4, connected to any suitable hoisting mechanism not 110 shown.

In order to take the strain off the cables I, I provide an adjustable strut consisting of the telescopic members J and J', which may be clamped at the desired position by 115 means of the set screws j.

At the upper end of the conveyer frame H' I provide a secondary frame H² in which is mounted the shaft h² of the grid screen K, having its sides formed with plates k. 120 The cross bar k' at the rear end of this grid is adjustably suspended by the rods k² screw-threaded at the upper end to engage a nut k³ resting upon the cross piece h³ carried by the arms H³ projecting rearward 125 from the conveyer frame H'.

By screwing up or easing off on these nuts k³, the inclination of the grid may be varied within desired limits.

At the bottom of the grid I provide a 130

canvas sampling chute L, which normally swings out of the way, as shown in Fig. 4, and which may be raised by means of the arm l and rod L', see Fig. 1, so as to conduct 5 a suitable amount of the material being treated into the receptacle L², such portion providing samples of material handled after screening. The dirt and other foreign matter falling through the inclined grid K is deflected to one side or the other of the inclined V-shaped hood N, by means of one or the other of the deflecting plates or apron M or M', see Fig. 6. There are two 10 of these deflecting plates or apron hinged together, as at m, and connected to the pulley m' which travels in the slotted cross bar H⁴ carried by the conveyer frame, and the said pulley may be drawn to one side or the other by means of the hauling lines M² 15 or M³.

When the pulley m' is drawn to the right, the deflecting plate M deflects the dirt to the inclined face n' of the hood N, as shown in full lines in Fig. 6, and if the pulley be 20 drawn to the opposite side of the frame, as indicated in dotted lines in Fig. 6, the dirt will then be deflected to the inclined face n² of the hood N.

At each side of the hood I provide endless 25 conveyers P and P', which receive the dirt and carry it above the adjustable dumping platform E, so that it may be dumped into the carts, wagons, or cars at either side of said platform and carried away, as will be 30 hereinafter described.

At their rear ends these conveyers P and P' are provided with belt tightening arrangements P⁰, and at their front ends these conveyers are pivoted on the axle P², and 35 each conveyer passes over a drum P³ fast on said shaft P². This shaft is driven by the pulley P⁴, as will be hereinafter described.

These conveyers dump the dirt from the upper ends into the hopper Q. The bottom 40 of this hopper is in the form of an inverted V, see Fig. 8, and the hopper is provided with two oppositely-disposed pockets q and q' which are normally closed by the doors Q', hinged at their bottoms as at q⁰ to the 45 hopper, which doors may be drawn up by the ropes or chains q³, passing over the pulleys q⁴, all as shown in Fig. 8.

So as to prevent the doors from swinging down too far, and to enable the doors to constitute a chute as illustrated in dotted lines 50 at the right of Fig. 8, I provide projecting lugs q² at the rear of each door, which engage beneath the bottom of the hopper when the door is swung to the open position as 55 shown in Fig. 8, and thus these doors serve as chutes to guide the dirt into the wagons, as shown in Fig. 3.

The three conveyers G, P and P' may be 60 driven by means of a single cable or rope R, see Fig. 1, passing over the driving pul-

ley R', thence over the pulley P⁴ for driving the dirt conveyers P and P', thence under and over the idler R², back to the pulley G³ for driving the conveyer G, thence over the idler R³ under the weighted pulley R⁴, which 70 keeps the cable under tension, thence over the pulley R⁵, back to the driving pulley R'. This driving pulley R' is driven in any convenient way and by any suitable source of power. 75

I have shown, in Fig. 1, an electric motor S driving the pulley S', which drives the pulley R⁰ fast on the same shaft with the driving pulley R'.

In order to conveniently feed the products 80 to be treated to the feed tables E and to use the same power apparatus for this purpose as is used in driving the several conveyers hereinbefore referred to, I provide apparatus which will be hereinafter described, with special reference to Figs. 1, 2, 85 3, 3^a, 3^b and 8.

There are two frames T adapted to be mounted on opposite sides of the feed table, which frames are mounted on pedestals t 90 adapted to rest on the ground so as to enable the frames to be moved when desired; and these frames are provided near their upper ends with journal bearings t' adapted to receive the spherical journal u of the 95 shaft U, which shaft carries a winding drum U' on which the rope or cable U⁰ is wound.

There is one of these shafts U at each side of the apparatus, which shaft is connected at its inner ends by the universal joint u' 100 to the stub shaft U², carrying the bevel gear U³ and the clutch members u² controlled by the lever u³ and the rope u⁴. These stub shafts U² are also provided with band brakes U⁴ operated by the levers u⁵ and ropes u⁶, 105 as shown in Figs. 3 to 3^b.

These several ropes pass through leads in a control board Z, so that all may be operated from the wagons as they drive up.

The bevel gears U³ are normally loose on 110 the corresponding stub shaft U², unless connected thereto by the clutch mechanism just referred to.

These bevel gears U³ are driven by the bevel gear V on the shaft V', see Figs. 2 and 115 3, and this shaft V' has a bevel gear V² meshing with the bevel gear V³ on the shaft P², which is driven by the pulley P⁴, as hereinbefore described. By this arrangement either of the drums U' may be caused to rotate by pulling on one or the other of the ropes u⁶, see Fig. 3; and the corresponding rope U⁰ will be wound up, tilting the wagon body W' of the corresponding wagon W, 120 as shown to the right of Fig. 3. 125

The opposite wagon shown in Fig. 3 is presumed to have been emptied and ready to receive such dirt as has accumulated in the left-hand side of the dirt hopper. As the wagon body is tilted, the side w is let 130

down so that the load in the wagon may be conveniently dumped on the adjustable feed table E.

X represents a canvas apron adapted to be connected to the wagon, and to the directing boards E², and into which the fine dirt from the bottom of the wagon will fall through the crack next the open side.

The operation of the complete apparatus 10 is as follows:—

The wagons are driven up opposite the feed tables E, the rope U⁰ is hooked beneath the body of the wagon at one side, the opposite side of the wagon is let down, and the wagon is tilted, as shown to the right of Fig. 3. The contents of the wagon will be dumped on the feed floor, and the speed with which the load falls on the conveyer G will be determined by the size of the throat or opening between the two oppositely disposed sliding tables E.

As the conveyer apron G passes beyond the frame H and reaches the frame H', its centre will sag down on the V-shaped rollers g⁴, forming a trough toward the center of which the beets or other products being treated will tend to settle by gravity. As the beets reach the upper end of the conveyer frame H' they will be dumped from the conveyer on to the grid K, and will fall on the pile in the process of being formed, or samples may be selected from the sampling chute L.

The dirt falling through the grid will be directed to one or the other of the dirt conveyers P or P' and will be carried upward and dumped into one side or the other of the hopper Q according to the position of the deflecting plates or apron M and M'. The dirt accumulating in the hopper Q may be dumped into one of the wagons which has just been emptied, as hereinbefore described, and carried back to the field, or other place where it is desired to deposit same. This dirt may be released from the hopper by simply easing up on the corresponding rope q³, and the weight of the dirt on the door will swing the same from the closed to the open position as shown to the right of Fig. 8.

The wagons are driven up into the spaces between the feed table E and the frame T.

When it is desired to move the apparatus for any reason, as from the growth of the pile to which the products have been applied, the main frame A may be moved to the desired position traveling on the wheels B, and the frames T may also be moved along at the same time.

By having the ball and socket bearing for the shaft U at the top of each frame T, and also having the inner end of the said shaft connected to its corresponding stub shaft by a universal joint, it will not be necessary to have the shaft U in exact alinement with the

corresponding stub shaft U² and great flexibility of parts is secured. When it is desired to move the apparatus for any considerable distance the shafts U will be entirely dismounted and moved separate from the frames T.

The main frame may be moved by a tractor, or by any suitable power, but I have shown in Fig. 1 a winch Y, driven by the motive power of the apparatus, to which a cable may be attached, and the cable may be connected to a stub-post, or other fixed body, and the wheels being set to the desired position, the main frame A may be moved in the desired direction by rotating this winch, as is well known in the use of dredge boats for digging canals, etc.

It will thus be seen that I provide in a single apparatus means for dumping the wagons, for adjusting the feed to the elevator, for elevating the products, separating the dirt and foreign matter from same, and carrying this dirt and foreign matter back to a hopper located above the wagons by means of which from time to time the accumulated dirt may be dumped into an empty wagon and removed.

It will be obvious that various modifications might be made in the herein described apparatus, and in the construction, combination and arrangement of parts which could be used without departing from the spirit of my invention, and I do not mean to limit the invention to such details except as particularly pointed out in the claims.

Having thus described my invention what I claim and desire to secure by Letters Patent of the United States is:—

1. Apparatus of the character described comprising a dumping platform, an endless conveyer passing beneath said platform, an inclined grid at the delivery end of said conveyer, a hopper having an inverted V-shaped bottom beneath said grid, means for deflecting the foreign matter dropping through said grid to one side or the other of said hopper, as desired, a second hopper mounted above the dumping platform, and endless conveyers located at each side of the first mentioned hopper for carrying away the material screened through said grid and returning same to the second hopper, substantially as described.

2. Apparatus of the character described comprising a dumping platform, an endless conveyer passing beneath said platform, an inclined grid at the delivery end of said conveyer, a hopper having an inverted V-shaped bottom beneath said grid, means for deflecting the foreign matter dropping through said grid to one side or the other of said hopper, as desired, a second hopper mounted above the dumping platform, and endless conveyers located at each side of the first mentioned hopper for carrying away

the material screened through said grid and returning same to the second hopper, with a driving engine and a cable or rope and pulleys operated thereby for simultaneously 5 operating all of said conveyers, substantially as described.

3. Apparatus of the character described comprising a dumping platform having a feed slot therein with means for varying 10 the width of said slot, an endless conveyer passing beneath said platform, an inclined grid at the delivery end of said conveyer, a hopper having an inverted V-shaped bottom beneath said grid, means for deflecting the 15 foreign matter dropping through said grid to one side or the other of said hopper, as desired, a second hopper mounted above the dumping platform, and endless conveyers located at each side of the first mentioned 20 hopper for carrying away the material screened through said grid and returning same to the second hopper, substantially as described.

4. Apparatus of the character described comprising a dumping platform having a feed slot therein with means for varying the width of said slot, an endless conveyer passing beneath said platform, an inclined grid at the delivery end of said conveyer, a hopper having an inverted V-shaped bottom beneath said grid, means for deflecting the foreign matter dropping through said grid to one side or the other of said hopper, as desired, a second hopper mounted above the 30 dumping platform, and endless conveyers located at each side of the first mentioned hopper for carrying away the material screened through said grid and returning same to the second hopper, with a driving 35 engine and a cable or rope and pulleys operated thereby for simultaneously operating all of said conveyers, substantially as described.

5. Apparatus of the character described comprising a dumping platform, an endless conveyer passing beneath said platform, an inclined grid at the delivery end of said conveyer, a hopper having an inverted V-shaped bottom beneath said grid, a pair of 45 deflecting plates hinged together and movable transversely for deflecting the foreign matter dropping through said grid to one side or the other of said hopper, as desired, a second hopper mounted above the dumping platform, and endless conveyers located at each side of the first mentioned hopper for carrying away the material screened through said grid and returning same to the second hopper, substantially as described.

6. Apparatus of the character described comprising a dumping platform, an endless conveyer passing beneath said platform, an inclined grid at the delivery end of said conveyer, a hopper having an inverted V-shaped bottom beneath said grid, a pair of deflect-

ing plates hinged together and movable transversely for deflecting the foreign matter dropping through said grid to one side or the other of said hopper, as desired, a second hopper mounted above the dumping 70 platform, and endless conveyers located at each side of the first mentioned hopper for carrying away the material screened through said grid and returning same to the second hopper, with a driving engine and a cable or rope and pulleys operated thereby for simultaneously operating all of said conveyers, substantially as described.

7. Apparatus of the character described comprising a dumping platform having a feed slot therein with means for varying the width of said slot, an endless conveyer passing beneath said platform, an inclined grid at the delivery end of said conveyer, a hopper having an inverted V-shaped bottom beneath said grid, a pair of deflecting plates hinged together and movable transversely for deflecting the foreign matter dropping through said grid to one side or the other of said hopper, as desired, a second hopper 85 mounted above the dumping platform, and endless conveyers located at each side of the first mentioned hopper for carrying away the material screened through said grid and returning same to the second hopper, substantially as described.

8. Apparatus of the character described comprising a dumping platform having a feed slot therein with means for varying the width of said slot, an endless conveyer passing beneath said platform, an inclined grid at the delivery end of said conveyer, a hopper having an inverted V-shaped bottom beneath said grid, a pair of deflecting plates hinged together and movable transversely 100 for deflecting the foreign matter dropping through said grid to one side or the other of said hopper, as desired, a second hopper mounted above the dumping platform, and endless conveyers located at each side of the first mentioned hopper for carrying away the material screened through said grid and returning same to the second hopper, with a driving engine and a cable or rope and pulleys operated thereby for simultaneously 105 operating all of said conveyers, substantially as described.

9. Apparatus of the character described comprising a dumping platform, an endless conveyer passing beneath said platform, an inclined grid at the delivery end of said conveyer, a hopper having an inverted V-shaped bottom beneath said grid, means for deflecting the foreign matter dropping through said grid to one side or the other of said hopper, as desired, a second hopper 120 mounted above the dumping platform, having pockets with outwardly inclined bottoms on each side thereof, with hinged doors normally closing said pockets, and endless 125

65 bottom beneath said grid, a pair of deflect-

130

conveyers located at each side of the first mentioned hopper for carrying away the material screened through said grid and returning same to the second hopper, substantially as described.

10. Apparatus of the character described comprising a dumping platform, an endless conveyer passing beneath said platform, an inclined grid at the delivery end of said conveyer, a hopper having an inverted V-shaped bottom beneath said grid, means for deflecting the foreign matter dropping through said grid to one side or the other of said hopper, as desired, a second hopper 15 mounted above the dumping platform having pockets with outwardly inclined bottoms on each side thereof, with hinged doors normally closing said pockets, and endless conveyers located at each side of the first mentioned hopper for carrying away the material screened through said grid and returning same to the second hopper, with a driving engine and a cable or rope and pulleys operated thereby for simultaneously operating all of said conveyers, substantially as described.

11. Apparatus of the character described comprising a dumping platform having a feed slot therein with means for varying the width of said slot, an endless conveyer passing beneath said platform, an inclined grid at the delivery end of said conveyer, a hopper having an inverted V-shaped bottom beneath said grid, means for deflecting the foreign matter dropping through said grid to one side or the other of said hopper, as desired, a second hopper mounted above the dumping platform having pockets with outwardly inclined bottoms on each side thereof, with hinged doors normally closing said pockets, and endless conveyers located at each side of the first mentioned hopper for carrying away the material screened through said grid and returning same to the second hopper, substantially as described.

12. Apparatus of the character described comprising a dumping platform having a feed slot therein with means for varying the width of said slot, an endless conveyer 50 passing beneath said platform, an inclined grid at the delivery end of said conveyer, a hopper having an inverted V-shaped bottom beneath said grid, means for deflecting the foreign matter dropping through said grid to one side or the other of said hopper, as desired, a second hopper mounted above the dumping platform having pockets with outwardly inclined bottoms on each side thereof, with hinged doors normally closing said 55 pockets, and endless conveyers located at each side of the first mentioned hopper for carrying away the material screened through said grid and returning same to the second hopper, with a driving engine and a cable or rope and pulleys operated thereby for

simultaneously operating all of said conveyers, substantially as described.

13. Apparatus of the character described comprising a dumping platform, an endless conveyer passing beneath said platform, an inclined grid at the delivery end of said conveyer, a hopper having an inverted V-shaped bottom beneath said grid, a pair of deflecting plates hinged together and movable transversely for deflecting the foreign matter dropping through said grid to one side or the other of said hopper, as desired, a second hopper mounted above the dumping platform having pockets with outwardly inclined bottoms on each side thereof, with hinged doors normally closing said pockets, and endless conveyers located at each side of the first mentioned hopper for carrying away the material screened through said grid and returning same to the second hopper, substantially as described.

14. Apparatus of the character described comprising a dumping platform, an endless conveyer passing beneath said platform, an inclined grid at the delivery end of said conveyer, a hopper having an inverted V-shaped bottom beneath said grid, a pair of deflecting plates hinged together and movable transversely for deflecting the foreign matter dropping through said grid to one side or the other of said hopper, as desired, a second hopper mounted above the dumping platform having pockets with outwardly inclined bottoms on each side thereof, with hinged doors normally closing said pockets, and endless conveyers located at each side of the first mentioned hopper for carrying away the material screened through said grid and returning same to the second hopper, substantially as described.

15. Apparatus of the character described comprising a dumping platform having a feed slot therein with means for varying the width of said slot, an endless conveyer passing beneath said platform, an inclined grid at the delivery end of said conveyer, a hopper having an inverted V-shaped bottom beneath said grid, a pair of deflecting plates hinged together and movable transversely for deflecting the foreign matter dropping through said grid to one side or the other of said hopper, as desired, a second hopper mounted above the dumping platform having pockets with outwardly inclined bottoms on each side thereof, with hinged doors normally closing said pockets, and endless conveyers located at each side of the first mentioned hopper for carrying away the material screened through said grid and returning same to the second hopper substantially as described.

16. Apparatus of the character described

- comprising a dumping platform having a feed slot therein with means for varying the width of said slot, an endless conveyer passing beneath said platform, an inclined grid 5 at the delivery end of said conveyer, a hopper having an inverted V-shaped bottom beneath said grid, a pair of deflecting plates hinged together and movable transversely for deflecting the foreign matter dropping 10 through said grid to one side or the other of said hopper, as desired, a second hopper mounted above the dumping platform having pockets with outwardly inclined bottoms on each side thereof, with hinged doors normally closing said pockets, and endless conveyers located at each side of the first mentioned hopper for carrying away the material screened through said grid and returning same to the second hopper, with a 15 driving engine and a cable or rope and pulleys operated thereby for simultaneously operating all of said conveyers, substantially as described.
17. Apparatus of the character described, comprising a feed platform, an endless conveyer passing beneath said platform, means for screening the foreign matter from the material on said conveyer, a pair of return conveyers for the screenings, and a driving 20 engine with a cable or rope and pulleys operated thereby for simultaneously operating all of said conveyers, substantially as described.
18. Apparatus of the character described, comprising a dumping platform, an endless conveyer passing beneath said platform, means for screening the foreign matter from the material being treated, means for deflecting the foreign matter to one side or the 25 other of said conveyer as desired, a hopper mounted above the dumping platform, and endless conveyers located at each side of said first-mentioned conveyer for carrying away the screenings and returning same to the said 30 hopper, substantially as described.
19. Apparatus of the character described,
- comprising a dumping platform, an endless conveyer passing beneath said platform, means for screening the foreign matter from the material being treated, means for deflecting the foreign matter to one side or the 35 other of said conveyer as desired, a hopper mounted above the dumping platform, and endless conveyers located at each side of said first-mentioned conveyer for carrying away the screenings and returning same to the said 40 hopper, substantially as described. 50
- comprising a dumping platform, an endless conveyer passing beneath said platform, means for screening the foreign matter from the material being treated, means for deflecting the foreign matter to one side or the other of said conveyer as desired, a hopper mounted above the dumping platform, and endless conveyers located at each side of said first-mentioned conveyer for carrying 55 away the screenings and returning same to the said hopper, with a driving engine and a cable or rope and pulleys operated thereby for simultaneously operating all of said conveyers, substantially as described. 60
20. Apparatus of the character described, comprising a main frame and wheels supporting same, a feed platform carried by said main frame, an endless conveyer also carried by said main frame and passing beneath said feed platform, means for driving said endless conveyer, a pair of auxiliary frames spaced away from said platform, flexible shafts each journaled at one end in said auxiliary frame and projecting inward 65 above said feed platform, a winding drum on each shaft, and means for rotating said shafts operated by said conveyer driving means, substantially as described. 70
21. Apparatus of the character described, comprising a main frame and wheels supporting same, a feed platform carried by said main frame, an endless conveyer also carried by said main frame and passing beneath said feed platform, means for driving 75 said endless conveyer, a pair of auxiliary frames spaced away from said platform, flexible shafts each journaled at one end in said auxiliary frame and projecting inward above said feed platform, a winding drum 80 on each shaft, and means for rotating said shafts operated by said conveyer driving means, with clutch mechanism operable by hand for throwing either of said shaft rotating means into operation, substantially as 85 described. 90
